(57) **CLAIM**

The ornamental design for a shoe, as shown and described.

DESCRIPTION

FIG. 1 is a side view of a shoe showing my new design; FIG. 2 is a rear perspective view thereof; FIG. 3 is a rear view thereof; FIG. 4 is an opposite side rear perspective view thereof; FIG. 5 is an opposite side view thereof; FIG. 6 is a side view of the shoe of FIGS. 1-5 shown in a second state with the removable pocket removed; FIG. 7 is a rear perspective view thereof; FIG. 8 is a rear view thereof; FIG. 9 is an opposite side rear perspective view thereof; and, FIG. 10 is an opposite side view thereof.

The broken lines immediately adjacent to the shaded area define the bounds of the claimed design and form no part thereof. The broken lines within the shaded area show portions of the shoe that form no part of the claimed design. In FIGS. 6-10, the broken lines showing of the circular shaped elements form no part of the claimed design. The broken lines depicting the zipper pull and the remainder of the shoe form no part of the claimed design.
